Primary Examiner—Philip S Hyder*Assistant Examiner*—Cynthia M Chin(74) *Attorney, Agent, or Firm*—Day Pitney LLP(57) **CLAIM**

The ornamental design for a cubical building element, as shown and described.

DESCRIPTION

FIG. 1 is a perspective view of my cubical building element design;

FIG. 2 is a plan view of a face of the cubical building element of FIG. 1, the remaining five faces being identical;

FIG. 3 is a perspective view of an alternate embodiment of my cubical building element design; and,

FIG. 4 a plan view of a face of the cubical building element of FIG. 3, the remaining five faces being identical.
